DESIGN FOR A BRAKE LEVER OR SIMILAR ARTICLE

Dorman B. Dickerson, Detroit, Mich.

Application March 5, 1938, Serial No. 75,622

Term of patent 7 years

To all whom it may concern:

Be it known that I, Dorman B. Dickerson, a citizen of the United States, and a resident of the city of Detroit, in the county of Wayne and State of Michigan, have invented a new, original, and ornamental Design for a Brake Lever or Similar Article, of which the following is a specification, reference being had to the accompanying drawing, forming a part thereof.

On the drawing:

Figure 1 is a side elevational view of the brake lever showing my new design.

Figure 2 is a front elevational view thereof.

The dominant feature of my design resides in the parts shown in full lines.

I claim:

The ornamental design for a brake lever or similar article, as shown and described.

DORMAN B. DICKERSON.
